ATTORNEY.

UNITED STATES PATENT OFFICE.

JOHN F. SALCHLI, OF FRANKFORT, KENTUCKY.

HAM-HOLDER.

1,199,500.

Specification of Letters Patent. Patented Sept. 26, 1916.

Application filed June 21, 1916. Serial No. 104,868.

To all whom it may concern:

Be it known that I, JOHN F. SALCHLI, a citizen of the United States, residing at Frankfort, in the county of Franklin, State 5 of Kentucky, have invented a new and useful Ham-Holder, of which the following is a specification.

This invention relates to apparatus designed to hold a cooked ham in a favorable 10 position for slicing.

In hotels, restaurants, and other places where boiled, or baked ham is served, the problem of cutting it is a considerable one. For the sake of economy the slices must be 15 thin, and for the sake of appearance they should be of uniform thinness, and as large as possible. The shape of a ham is such that it is difficult to hold steady while operating upon it. The usual practice is to lay 20 the ham upon a table and grasping the small end thereof with one hand, manipulate the carving knife with the other, meantime turning the ham slowly.

An object of this invention is to provide 25 means whereby a ham may be supported in a favorable position for slicing and rigidly held against any movement except such as will assist in the slicing operation.

A further object is the provision of means 30 of the character set forth which will be economical in construction, efficient in operation and durable in service.

With the foregoing and other objects in view, the invention consists of the novel 35 construction and arrangement of parts illustrated in the accompanying drawing, which forms a part of this specification, wherein is set forth an embodiment of the invention, but it is to be understood that such changes 40 and modifications may be resorted to as come within the scope of the claims appended hereunto.

Referring now to the drawing, wherein 45 similar reference characters designate like parts in the several views, Figure 1, is a perspective view of my improved device, a ham held by same being shown in dotted lines: Fig. 2, a vertical section on line 2 of Fig. 1: Fig. 3, a perspective view of one of the 50 upright members: and Fig. 4, a perspective view of one of the side members.

The embodiment of the invention illustrated herewith comprises a base —1— adapted to be placed upon a suitable support, such as a table, or stand, and be re-

tained in place thereon by suitable means such as a C clamp —2— which is provided with a screw —3— which may be contacted with the underside of the table. The upper surface of the base is provided with a plurality of marginal serrations, or ratchet teeth —4—. A platform —5— rests upon the base, and is provided with a plurality of serrations, or ratchet teeth —6— which coöperate with the ratchet teeth on the base 60 to permit the platform to turn in one direction only. The platform is held in rotatable relationship to the base by means of a central bolt —7—, this bolt has sufficient vertical play to permit the ratchet teeth on the 65 platform to ride over the teeth in the base as the platform is turned in the only permissible direction. Withdrawal of the bolt 7 is prevented by suitable means such as a pin —8—.

A pair of laterally movable clamping members —9— and —10— are pivotally mounted on the upper surface of the platform by suitable means such as a screw —11—. The outer, or free ends of these 80 members have suitable means, such as a bolt —12—, provided with a thumb nut —13—, by means of which they can be securely clamped about the small, or hock end —15—, of a ham, they being suitably contoured to fit thereabout. Suitable means are provided to prevent lateral movement of the members when clamped together, as illustrated this means comprises a post —16— extended from the platform and lying between the two members. Staples —17— disposed on the edges of the platform at diametrically opposed points, preferably in alignment with the screw 11 and post 16, provide means whereby supporting members —18, 19— may be movably connected to the platform. Hooks —20— on the lower ends of the supporting members provide means of engagement with the staples. These supporting members are shaped to conform, roughly, with the contour of the edge of the lower portion of a ham, and extend upward approximately half the height of a ham. The supporting member 18 is provided at its upper end with means for connection 95 therewith of a pair of holding members —21—. As illustrated the connecting means between the member 18 and the members 21, comprise a pair of vertical slots —22— at the upper end of the member 18, 110

and a recurved portion, or hook —23— on one end of each of the members 21, adapted to be inserted in said slots. The members 21 are contoured to conform, roughly, to the 5 sides of a ham, and may be provided on their inner sides with a plurality of spurs —24— adapted to be engaged in the ham and prevent any shifting thereof. The member 19 has a T shaped head —25— having on its 10 upper surface a plurality of recesses —26— in which the free ends of the holding members 21 may be placed, to hold them against the ham. Notches —27— near the free ends of the holding member are to be engaged 15 with the body of the head after the member is inserted in a slot.

In preparing my device for service, a ham is stood on its small end, or hock, in the center of the platform, the clamping 20 members 9, 10, brought into contact therewith and secured by means of the bolt 12. The supporting members are placed in position by inserting the hooks 20 in the staples 17. The holding members 21 are then connected with the upright 18, by inserting the 25 hooks 23 in the slots 22. The holding members are then swung into contact with the ham and the free ends thereof engaged in the slots 26 in the upper end of the upright 30 19. The slicing may then be proceeded with, the operator holding a knife in a horizontal position and drawing it through the ham from the side opposite the operator, toward the bone. After each cut, the ham 35 may be slightly turned, so that the ham will be cut away equally all around.

Having thus described my invention so that anyone skilled in the art pertaining thereto may make and use the same, I 40 claim:

1. In a device of the character described, a base, a pair of clamping members mounted thereon, supporting elements detachably engaged therewith, a pair of holding members 45 in pivotal engagement with one of said elements and means for connecting said members with the other of said elements.

2. In a device of the character described, a platform provided with oppositely disposed peripheral slots, uprights removably positioned in said slots, one of said uprights being provided with a plurality of slots, laterally movable members detachably engaged in said slots, and means for connect-

ing said members in locking engagement 55 with the other of said uprights.

3. In a device of the character described, a base, a platform rotatably mounted thereon, means to prevent retrograde movement thereof, uprights removably positioned on 60 said platform, laterally movable members connected with one of said uprights, and means for connecting said members in locking engagement with the other of said uprights.

4. In a device of the character described, a base, a platform rotatably mounted thereon, means to prevent retrograde movement thereof, uprights removably positioned on said platform, laterally movable members connected with one of said uprights, the other of said uprights having a plurality 70 of notches, or recesses adapted to receive said members, said members being provided near their free ends with notches adapted to engage with the upright at the bottom of said recesses.

5. In a device of the character described, a base, a platform rotatably mounted thereon, means to prevent retrograde movement 80 thereof, means carried by said platform adapted to be seized on the hock end of a ham, and means detachably engaged with said platform and adapted to be engaged with the ham intermediate its length.

6. In a ham holder, a base provided with ratchet teeth on its upper surface, a platform rotatably mounted thereon having ratchet teeth adapted to coöperate with those of the base and means carried by said platform for holding a ham in a favorable position for slicing.

7. In a ham holder, a base provided with ratchet teeth on its upper surface, a platform rotatably mounted thereon, means for 95 centering a ham on the platform and means connected to the platform for grasping the ham intermediate its length.

8. In a ham holder, a base provided with ratchet teeth on its upper surface, a platform rotatably mounted thereon, means connected with said platform coöperating with said teeth to prevent retrograde movement of the platform, means for centering a ham on the platform and means connected to the 105 platform for grasping the ham intermediate its length.

JOHN F. SALCHLI.
